UNITED STATES PATENT OFFICE.

JOHN W. ESTES, OF DIXON, MISSOURI.

COMBINATION-LOCK.

SPECIFICATION forming part of Letters Patent No. 369,331, dated September 6, 1887.

Application filed July 9, 1886. Serial No. 207,541. (Model.)

To all whom it may concern:

Be it known that I, JOHN W. ESTES, a citizen of the United States, residing at Dixon, in the county of Pulaski and State of Missouri, 5 have invented certain new and useful Improvements in Combination-Locks; and I do hereby declare the following to be a full, clear, and exact description of the invention, such as will enable others skilled in the art to which it applies to make and use the same.

My invention relates to improvements in combination-locks, the object of which is to provide a cheap, simple, durable, and convenient device for being used either as a padlock, door-lock, drawer, safe, or chest lock, &c. These objects I attain by means of the device illustrated in the accompanying drawings, forming a part of this specification, in which—

20 Figure 1 is a view in elevation of my invention, as seen from the outside, applied to a trunk-lock. Fig. 2 is a similar view applied to a padlock. Fig. 3 is a view of the interior of the lock, with the plate, dial, and upper 25 tumbler removed. Fig. 4 is a view in elevation of the upper tumbler from the under side secured to the plate, and also showing the back side of the dial as secured to said plate. Fig. 5 is a view of the hasp and its attachments when used with a trunk-lock. Fig. 6 30 is a view of the lower tumblers. Fig. 7 is a view of the face of the dial. Fig. 8 is a view of the knob and hand for setting the combination. Fig. 9 is a view of the plate from the 35 back side. Fig. 10 is a view of the upper tumbler from the upper side. Fig. 11 is a view of the washer to be used on the post of the lock.

Similar letters of reference represent corresponding parts in the several figures.

A is the casing, of any desired size and shape to hold the mechanism of the lock. Said casing has a rim, a, in which are formed holes a² a² to receive the hasp, and an opening, a³, to 45 receive a lug, b, of the dial B. Said dial is also provided with a projection, b², in which are holes b³ b³ to receive the hasp C, for holding the dial firmly in place. The face of said dial is divided into any given number of parts, 50 which are indicated by marks, and are num-

bered, so that the combinations may be easily noted or remembered. It is also provided with a hole, b⁴, to admit light into the interior of the casing when setting the combination, and a central hole to receive the neck of the 55 plate.

D is a plate of any desired size, preferably large enough to cover the dial B, and has a neck, d, provided with a shoulder, d². Said plate turns in the opening in the dial on the 60 large part d³ of the neck, serving as an axis, while the first or upper tumbler, E, is secured firmly in place upon the shoulder d², said shoulder being provided with teeth d⁴, for engaging similar teeth, e, on the upper side of the tumbler E, for preventing the same from turning. Said tumbler is secured in place by means of a set-screw, d⁵, which enters the opening d⁶ in the end of the neck d. Said plate D has an opening, d⁸, provided with a pointer, d⁹. Tumbler E is circular in shape and provided with a notch, e², in the margin of the same. One side, e³, of the said notch is cut on the radial line from the center of the tumbler, the other side, e⁴, being a gradual descent to the desired 65 depth, for letting the catch l of the bolt enter the notches g² f² of the lower tumblers in locking, and for removing the same when unlocking. Said tumbler has a pin, e⁵, which is placed about 70 one-fourth the distance around the tumbler 75 from the said notch. Said pin is adapted to enter slots f g in the other tumblers, which may be of any desired number, preferably two, F G, as shown. Said tumblers are circular in form, and have bearings on the post a¹, and between 80 them is placed a stationary washer, H, which is secured to said post by any suitable means, preferably by means of a tooth, h, which enters a groove, a⁵, in such post, thus preventing the under tumblers from interfering with each 85 other when in motion. Said tumblers have notches g² f² in their outer edges, with radial sides made large enough to receive and hold the catch l of the lock-bolt L when the device is unlocked.

95 L is a bolt, of any desired size and shape, provided with a slot, l², to receive a lug in the casing for holding it in place. Said bolt has lugs l³ l⁴ to enter the notches of the hasp, and is provided with a suitable spring, I, for throw- 100

ing it and holding it back out of the way when unlocked.

5 C is a hasp, of any desired size and shape, and when used in connection with a trunk-lock, door-lock, &c., it is provided with a suitable lever, K, which has an arm, k^2 , engaging said hasp, a pivot, k^3 , and a thumb-piece, k^4 , which projects through a slot in the upper casing or plate, A³, to the outside, for raising said hasp, 10 when desired, after unlocking.

15 O is a setting-knob having shoulders o^2 o^3 and an opening to receive a set-screw, d^1 , which enters the end of the knob to hold the upper tumbler, E, in place, the same as said tumbler is secured to the neck of plate D. A post, a^4 , which is secured to the casing A, has an open top, or is hollow, to receive the head of said set-screw d^1 .

20 P is a hand secured to the setting-knob by means of an open ring, p. This setting-knob is used when it is desired to find or change the combination of the lock, as hereinafter explained.

25 A² is a plate for securing the lock in position to a trunk, chest, door, drawer, &c. It is provided with a hole to receive the casing of the lock, and also holes to receive bolts for securing the same.

30 A³ is an upper plate for securing the hasp to the top of the trunk, &c., and is provided with a lever, K, for operating the same, as above set forth.

35 The device is put together and operated thus: One of the lower tumblers is placed on the post a^4 . Then the stationary washer H is secured in position and the other tumbler placed on the post. The bolt L is placed so that the catch l will drop in the notches f^2 g^2 e^5 when the tumblers are in position. The dial 40 is then placed on the neck of the setting-knob for setting the combination, with its face toward the knob, while the tumbler E is secured firmly in place on the shoulder of the same to revolve with the knob. The lug b of the dial is then put in the opening a^3 , and the projection b^2 fits over the bolt L. The knob is then turned to the left and the edge of the upper tumbler moves the catch of the bolt back to catch the hasp in locking. Meanwhile the 45 pin e^4 moves the under tumblers, and by reason of the different lengths of the slots f g the notches f^2 g^2 are separated, so that the knob is free to move or revolve in either direction without setting the combination for 50 admitting the bolt to fly back, and different locks may have slots of different lengths in the tumblers relatively to each other for making different combinations.

55 The combination is learned by examination with the setting-knob thus: The setting-knob is turned in either direction, turning to the right until the longest slotted lower tumbler is set with its notch opposite the catch l of the bolt, which may be seen through the hole 60 b^4 in the dial, said hole being placed over the

70 catch l and large enough to admit light, so as to see the position of the tumblers. The pointer p^2 of the hand is then moved to any desired position on the dial, which is noted as the first part of the combination. The knob is then turned back in the opposite direction until the notch of the other tumbler is opposite the said catch, which is seen as before. The position of the pointer is then noted as the second part of the combination. 75 The knob is then turned back again in the first direction until the notch of the upper tumbler gets opposite the said catch, in which case the bolt is thrown and held back by the spring and the catch of the bolt enters the 80 notches. The position of the pointer is again noted as the third and last element of the combination. The setting-knob is then removed and the plate D secured in its place, the dial being placed on the neck as before. 85 The pointer d^0 is placed on the last part of the combination. The upper tumbler is then secured in position by the set-screw d^1 , so that the radial edge e^2 of the notch e^5 will be on a line with the line b^6 , which is placed on the 90 back of the dial, so as to be directly over the center of the catch l when the dial is in place on the lock. Thus, when put together and locked, which is accomplished, as above set forth, by turning the plate to the right, it 95 may be unlocked by turning said plate so that the pointer of the plate will move as the pointer of the setting-knob was moved, as shown by the dial.

100 The combination may be changed when desired by means of the setting-knob and placing the setting-pointer at a different position in the beginning.

This lock may be made of any suitable material, and having but one spring, which may be 105 easily replaced, it is very durable.

Having thus described my invention, what I claim as new, and desire to secure by Letters Patent, is—

1. In a lock, a dial, B, having a face marked 110 or divided into a number of parts, a lug, b, secured upon the back thereof, and a line, b^6 , also on the back thereof and over the center of catch l when the dial is in place on the lock, said dial being provided with a central 115 hole to admit the neck of the setting-knob O, and a hole, b^4 , and a projection with holes to receive a hasp, substantially as and for the purpose set forth.

2. In a lock, a plate, D, having a hole, d^8 , 120 and a pointer, d^0 , and provided with a neck, d , having a shoulder, d^2 , provided with teeth d^4 , substantially as and for the purpose set forth.

3. The combination, with a combination-lock, of a setting-knob, O, having shoulders o^2 o^3 , with a hand, P, a dial, B, having a face divided into a number of parts, and a tumbler, E, having a pin, e^4 , and notch e^5 , all 125 substantially as and for the purpose set forth. 130

4. The combination, with a lock-case and bolt provided with a spring, of a hasp, C, round tumblers F G E, having notches and slots, dial B, having a face divided into a 5 number of parts, plate D, having a neck, and plates A² A³, substantially as shown and described.

In testimony whereof I affix my signature in presence of two witnesses.

JOHN W. ESTES.
